UNITED STATES PATENT OFFICE.

FREDERICK HEATH, OF TACOMA, WASHINGTON.

REINFORCED BUILDING-WALL.

1,319,336.

Specification of Letters Patent. Patented Oct. 21, 1919.

Application filed February 20, 1918, Serial No. 218,259. Renewed August 19, 1919. Serial No. 318,591.

To all whom it may concern:

Be it known that I, FREDERICK HEATH, a citizen of the United States, and a resident of Tacoma, in the county of Pierce and State 5 of Washington, have made certain new and useful Improvements in Reinforced Building-Walls, of which the following is a specification.

My present invention relates generally to 10 reinforced building walls, and particularly to a building wall of the type described and claimed in my Patent 1,215,149, dated February 6, 1917, having simple, inexpensive reinforcing elements capable of utilization 15 either horizontally or vertically or both, my primary object being the provision of a wall of this type wherein reinforcing members may be utilized without changing or breaking the running joints of the blocks or tiles, 20 and without displacing or otherwise interfering with the alinement of the supporting webs.

As the description of my present improvements proceeds, it will be noted that my invention does away with a specially formed tile or block having a space provided to receive a metallic reinforcing bar, and that it obviates the necessity of cutting the tile or block to receive the bar.

It will be observed, furthermore, that the presence of the reinforcing members does not interfere with the bedding of the tiles or blocks, and certain other advantages will be noted in the course of the detailed explanation to follow.

In the accompanying drawing illustrating my present invention:—

Figure 1 is a perspective view illustrating a relatively narrow wall constructed in 40 accordance with my invention;

Fig. 2 is a similar view illustrating a somewhat wider form of a wall, and,

Fig. 3 is another similar view illustrating still a wider form of wall.

Referring now to these figures, it will be noted that as in my patent above referred to, the blocks or tiles are laid in horizontal courses, and that in proceeding vertically in the formation of the wall the blocks of each 50 course have their cross joints, that is the joints between their ends, in break joint relation to the cross joints of the courses above and below the same, so that the cross joints of alternate courses are in the same vertical 55 planes.

Referring now to Fig. 1, which shows a relatively narrow wall, the blocks 10 of alternate courses are of the full width of the wall and have voids 11 between and at opposite sides of vertically disposed supporting webs 12, which latter, it is to be noted, as well as the webs at the sides of the blocks 10, are alined, vertically throughout the series not only with the similar blocks of alternate courses, but with the vertical webs 13 of the blocks 14 of the other courses, which latter are separate from one another and have longitudinal or running joints 15 therebetween alined with the central voids 11 of the blocks 10. Thus the inner side 70 webs 13 of the blocks 14 are brought into register with the supporting webs 12 of the blocks 10, and the running joints 15 provide for the reception of horizontally disposed reinforcing rods 16, through those alternate 75 courses in which the blocks 14 occur, and also provide for the reception of vertically disposed reinforcing rods 17, which extend through the running joints 15 of those courses in which the blocks 14 occur, and 80 through the cross joints 18 of those courses in which the blocks 10 occur.

It is obvious, therefore, that the horizontal and vertical reinforcing bars 16 and 17 may be utilized without interfering in any respect with the laying of the tiles or blocks 10 and 14, or with the formation of the wall as the latter proceeds to completion, and it is also to be observed that the said reinforcing bars may, without extra work or trouble, 90 be firmly and rigidly united within the wall by grouting or cementing the same within both the running and cross joints of the blocks or tiles.

In a wall slightly greater in width than 95 that above described, and as seen in Fig. 2, where each course consists of two blocks 19 and 20, and each succeeding course is the same with the exception of the reversed order of these blocks, it is obvious that the 100 horizontal and vertical reinforcing bars 21 and 22 may be utilized either at one side or the other of the center of the wall or staggered throughout the wall, and it is further obvious from an inspection of Fig. 3, where 105 alternate courses contain two blocks 23 of the same type, and the other courses embodying three blocks 24 and 25 of which the block 25 alone is like the blocks 23 of the other alternate courses, it is obvious that 110

the horizontal and vertical bars 26 and 27 may be used either at the center or opposite sides or staggered throughout the wall, just as desired, the vertical reinforcing bars of 5 Figs. 2 and 3 extending through the running joints of certain courses and the cross joints of the other courses just as in Fig. 1.

It is therefore obvious that my invention 10 enables me to reinforce a wall of the type shown in my patent above referred to, and add to its strength in various degrees, inasmuch as it is obvious that the numbers of reinforcing rods of Figs. 2 and 3 may be greatly varied, as desired, and that even in 15 the wall shown in Fig. 1, the horizontal reinforcing bars 16 may be greatly varied as to number.

I claim:—

A reinforced building wall consisting of 20 blocks laid horizontally in courses, one above another, and of which certain courses at least comprise separate blocks in the width of the wall and have running joints between such blocks, the cross or end joints of the blocks of the several courses being arranged 25 in break-joint relation with the cross joints of alternate courses in vertical alinement, reinforcing bars extending vertically through the cross joints of alternate courses and the running joints of the other courses, and 30 other reinforcing bars extending horizontally through the running joints of the last mentioned courses.

FREDERICK HEATH.
